(57) **CLAIM**

The ornamental design for a container to transport chemical substances, as shown and described.

DESCRIPTION

1. Container to transport chemical substances

1.1 : Perspective

1.2 : Top

1.3 : Exploded with bottle and holder combined

1.4 : Perspective

1.5 : Exploded of bottle and holder

1.6 : Front of bottle and holder combined

1.7 : Perspective of holder

1.8 : Front of holder

1.9 : Perspective of holder

1.10 : Front of bottle

1.11 : Exploded

A container to transport chemical substances, comprising an outer container, a bottle, and holder for the bottle; the holder is fitted into the outer container during transportation.
